UNITED STATES PATENT OFFICE

110,299

DESIGN FOR A CRAVAT HOLDER

Bernard R. Zeman, Providence, R. I., assignor to Swank Products, Inc., a corporation of Delaware

Application April 28, 1938, Serial No. 76,781

Term of patent 14 years

To all whom it may concern:

Be it known that I, Bernard R. Zeman, a citizen of the United States, residing at Providence, county of Providence, and State of Rhode Island, have invented a new, original, and ornamental Design for a Cravat Holder, of which the following is a specification, reference being had to the accompanying drawing forming a part thereof.

Fig. 1 is a front elevation;

Fig. 2 is a view taken on substantially line 2—2 of Fig. 1; and

Fig. 3 is a perspective view of the cravat holder showing my new design, the initials shown in Fig. 1 being omitted for convenience of illustration.

I claim:

The ornamental design for a cravat holder, substantially as shown.

BERNARD R. ZEMAN.
